DOCTOR OPERATING MECHANISM FOR ROLLS AND CYLINDERS

Frederick W. Lodding, Worcester, Mass.

Application December 9, 1938, Serial No. 244,824

4 Claims. (Cl. 92—74)

The present invention relates to devices known in the paper making art as doctors or scrapers, such devices being customarily employed in connection with rotating calender rolls, press rolls, drier cylinders and the like, for the purpose of cleaning the surfaces of such rolls and cylinders.

In the operation of a doctor, it is desirable to move the doctor blade back and forth in a direction parallel to the axis of the rotating surface being doctored, since such reciprocatory movement tends to reduce and equalize wear on the roll surface, and obtains better results, for a given pressure exerted by the doctor blade. While mechanisms for imparting reciprocatory movement to doctors have heretofore been employed, such mechanisms have been in the nature of auxiliary attachments to existing doctor installations, with resulting complexity of construction and obstruction of space usually available for access to the doctors and roll surfaces. Furthermore, it has been found that in some doctor installations, space factors make it practically impossible to apply any auxiliary operating mechanism.

According to the present invention, there is provided an improved doctor-operating mechanism of the above described character, in which the mechanism for imparting reciprocatory movement is incorporated in the doctor assembly, so as to be disposed entirely within the pivotal supports for the doctor. As a result, doctor mechanisms embodying the present invention can be installed in any desired location with reference to rolls and cylinders, without having to consider space limitations which would render the application of an auxiliary operating mechanism impossible. The above and other advantageous features of the invention will hereinafter more fully appear from the following description with reference to the accompanying drawings, in which:

Fig. 1 is a view in end elevation, of a doctor mechanism embodying the present invention.

Fig. 2 is a longitudinal sectional view, along the line 2—2 of Fig. 1.

Fig. 3 is a fragmentary sectional view, illustrating, on an enlarged scale, the control valve mechanism indicated in Fig. 2.

Fig. 4 is a sectional view along the line 4—4 of Fig. 3, looking in the direction of the arrows.

Fig. 5 is a sectional view along the line 5—5 of Fig. 3, looking in the direction of the arrows.

Fig. 6 shows the valve mechanism of Fig. 3 in a different position.

Fig. 7 is a view in end elevation of a modified form of doctor operating mechanism.

Fig. 8 is a view partially in front elevation, and partially in section, along the line 8—8 of Fig. 7.

Like reference characters refer to like parts in the different figures.

Referring first to Figs. 1 and 2, a portion of the surface of a roll or cylinder is indicated at 10, and a doctor holder 2 is carried by an arm 3 pivotally mounted about an axis, parallel with respect to the axis of rotation of the roll 1. The holder 2 carries a doctor blade 4 of thin flexible material, and turning of the holder 15 about the pivotal axis of the arm 3, serves to bring the blade 4 into engagement with the rotating surface of the roll 1. The particular construction of the holder 2 and blade 4 forms no part of the present invention, which has to do with improved mechanism for imparting a reciprocatory movement to the holder 2, so that the blade 4 will move back and forth longitudinally of the surface being doctored.

The doctor-supporting arm 3 carries near its 25 ends a pair of trunnions providing cylindrical housings 5, within each of which is received a journal 6, rigidly mounted on a machine frame member 7. A suitable anti-friction bearing 8 is disposed between each journal 6 and the wall 30 of the surrounding housing 5, so that the arm 3, together with the holder 2 carrying the doctor blade 4, is free to turn about a pivotal axis parallel to the axis of rotation of the roll 1. Each journal 6 carries a piston 9 fitting closely within 35 a housing 5, both housings 5, together with the doctor arm 3, being capable of shifting movement as a unit on the stationary pistons 9. Each housing 5 is closed by a cap 10 beyond the piston 9, thereby providing an enclosed chamber 11 at the end of each housing 5.

As best shown in Figs. 3, 4 and 5, one chamber 11 provides a control valve mechanism, consisting of a lever 12, turnable on a pivot pin 13, mounted on a valve block 14 carried by the cap 10. The lower end of the lever 12 is connected by spring 15 to a stud 16 extending from the piston 9, so that movement of the housing 5 with respect to the piston 9, will impart turning movement to the lever 12.

The upper end of the lever 12 carries a valve disk 17, which, as best shown in Fig. 5, is movable with respect to a series of ports 18, 19 and 20, provided in the block 14. The port 18 is in communication with a passage 21 extending through the cap 10 to the outside atmosphere, while the

port 19 is connected by a passage 22, extending through the block 14 to a pipe 23 leading through the other cap 10 to the chamber 11, within the opposite housing 5. The third port, 20, is connected by a passage 24 to a pipe 25, leading to a suitable source of suction, not shown, such as is often available on paper making machines, for suction boxes.

With the valve lever 12 in the position of Fig. 3, the disk 17 bridges the ports 18 and 19, and a recess 17a within the disk 17 serves to connect the ports 18 and 19. As a result, the inside of the right-hand chamber 11 is open to atmospheric pressure through the pipe 23, the connected valve ports 18 and 19, and the passage 21. Consequently, when the left-hand chamber 11 is subjected to suction through the pipe 24 and the then open port 20, atmospheric pressure entering the right-hand chamber 11 and also acting against the exterior of the left-hand chamber cap 10, will cause the housing 5, and with it the arm 3 and doctor blade 4, to be shifted to the left, as viewed in Fig. 2.

When this shifting has caused the doctor blade 4 to reach the dotted line position of Fig. 2, movement of the pivot pin 13 for the lever 12, with respect to the fixed stud 16, will cause the spring 15 to throw the lever 12 from the position of Fig. 3 to the position of Fig. 6. When this occurs, the shifting of the valve disk 17, causes the port 18 to be uncovered, thereby admitting atmospheric pressure to the left-hand chamber 11. At the same time, the ports 19 and 20 will be placed in communication, thereby subjecting the right-hand chamber 11 to the source of suction, through the pipe 23. The resulting force of atmospheric pressure acting in the left-hand chamber 11, and against the right-hand chamber cap 10, with the right-hand chamber evacuated, will cause the arm 3 and doctor blade 4 to move to the right, until the parts reach the position of Fig. 2. The valve lever 12 will thereupon again establish connections for left-hand movement of the arm 3, so that as long as suction is supplied through the pipe 25, the arm 3 will automatically move back and forth to impart a reciprocatory movement to the edge of the blade 4 bearing on the surface of roll 1.

Such reciprocation of the blade 4, or "oscillation," as it is sometimes termed, is extremely effective in furthering the doctoring action of the blade in cleaning the roll 1, since it tends to reduce and equalize wear of the roll surface, such as would not otherwise occur. Furthermore, it is apparent that installation of complete means for imparting reciprocatory movement to the blade, is accomplished by merely mounting the supporting arm 3 between the journals 6, carried by the machine frame members 1. The fact that the entire operating mechanism is thus self contained within the extremities of the arm 3, makes it possible to readily install a reciprocating doctor in locations where space limitations would make it impossible to install an auxiliary doctor-operating mechanism. It is also to be noted that the provision of separate spaced chambers for the actuating medium, entirely eliminates the necessity for airtight stuffing boxes, such as would be required for a double acting cylinder utilizing a pressure medium.

Referring now to Figs. 7 and 8, there is shown a modified arrangement of the doctor-operating mechanism, in which the disposition of the machine frame members 1a permits a trunnion arrangement extending beyond the ends of the arm 3a carrying the holder 2 and doctor blade 4.

In this construction, each end of the arm 3a supports a projecting cylindrical trunnion housing 26, providing an external groove 27 for receiving a curved saddle 28, best shown in Fig. 7. Thus, the weight of the doctor supporting arm 3a and the housings 26, is supported by the saddles 28, with the entire assembly free to turn about an axis coinciding with the center of curvature of the saddles 28. Each saddle 28 is mounted for longitudinal movement on a pair of rollers 29, rotatably supported on divergent axes, by means of a bracket 30 secured to each frame member 1a.

Thus, the whole doctor assembly is pivotally supported as a unit for back and forth movement by a suction-controlled mechanism similar to that previously described with reference to Figs. 1 and 2.

Each housing 26 surrounds a stationary piston head 31, mounted on a rod 32 extending from a bracket 33 carried by a frame member 1a. The pistons 31 therefore define chambers 34 within the housings 26, and a valve operating lever 12a is mounted within one chamber 34, so as to function in exactly the same manner as the valve lever 12, previously described with reference to Figs. 3 to 6, inclusive. A pipe 35 leading from a suitable source of suction, leads into the left-hand chamber 34, while a pipe 36 connects the chambers, so that as suction and atmospheric pressure are alternately applied to the chambers 34, the entire doctor assembly moves back and forth on the rollers 29, it being noted that the pistons 31 are entirely relieved of the weight of the doctor assembly. Since the rods 32 carrying the stationary pistons 31 are adjustable within the brackets 33, the amplitude of the reciprocatory movement imparted to the doctor blade 4 can be readily varied by shifting the positions of the pistons 31 within the housings 26.

From the foregoing, it is apparent that by the present invention there is provided an improved mechanism for imparting a back and forth or oscillatory movement to doctor blades, particularly characterized by the mounting of the entire operating mechanism, to move as a unit with the arm which carries the doctor blade holder. While the operating mechanism has been described as being actuated from a suction source, obviously, it will function just as effectively when actuated by any pressure medium. For pressure operation, it is only necessary to connect a pipe leading from a pressure source to the valve passage 21, while allowing the valve port 20 to exhaust the chambers to the atmosphere alternately through functioning of the valve lever 12. In operation of the mechanism constructed as shown in Figs. 7 and 8, the amount of power required is small, due to the fact that the trunnion housings carrying the entire doctor assembly are supported for pivotal, as well as longitudinal, movement by the saddles and rollers entirely independent of the stationary pistons within the housings, so that frictional losses are reduced to a minimum.

I claim:

1. A doctor operating mechanism for rolls and cylinders of a paper making machine, comprising in combination, spaced stationary frame members, a doctor blade, a carrier for said blade extending between said frame members, trunnions mounted on said carrier at its ends and providing hollow housings, means for rotatably and slidably supporting said trunnion housings

on said frame members to position said carrier with the edge of said blade in engagement with a rotating surface, a piston carried by each frame member and extending within a trunnion housing, and valve means located in one housing and operated by relative movement between said housing and piston for controlling admission of a fluid operating medium to the trunnion housings, to impart a back and forth movement to said blade carrier with respect to said pistons and frame members, in a direction parallel to the axis of said rotating surface.

2. A doctor operating mechanism for rolls and cylinders of a paper making machine, comprising in combination, spaced stationary frame members, a doctor blade, a carrier for said blade extending between said frame members, trunnions mounted on said carrier at its ends, and each providing a hollow housing, with said trunnion housings being disposed entirely between the extremities of said blade carrier, journals extending from said frame members into said housings for rotatably and slidably supporting said trunnions and carrier, with the edge of said blade in engagement with a rotating surface, pistons carried by said journals and fitting within said housings, and valve means located in one housing and operated by relative movement between said housing and piston for controlling the admission of a fluid operating medium to the trunnion housings to impart a back and forth movement to said blade carrier with respect to said pistons and frame members, in a direction parallel to the axis of said rotating surface.

3. A doctor operating mechanism for rolls and cylinders of a paper making machine comprising in combination, spaced stationary frame members, a doctor blade, a carrier for said blade extending between said frame members, trunnions mounted on said carrier at its ends and

each providing a hollow housing extending beyond the end of said carrier, means cooperating with the exterior of said housings for rotatably and slidably supporting said trunnions on said frame members to position said carrier, with the edge of its blade in engagement with a rotating surface, pistons carried by said frame members and fitting within said trunnion housings, and valve means located in one housing and operated by relative movement between said housing and piston for controlling the admission of a fluid operating medium to the trunnion housings, to impart a back and forth movement to said blade carrier with respect to said pistons and frame members, in a direction parallel to the axis of said rotating surface.

4. A doctor operating mechanism for rolls and cylinders of a paper making machine, comprising in combination, spaced stationary frame members, a doctor blade, a carrier for said blade extending between said frame members, trunnions mounted on said carrier at its ends and each providing a hollow housing extending beyond the end of said carrier, saddles and rollers cooperating with said trunnions for rotatably and slidably supporting said carrier and blade assembly on said frame members to position said carrier, with the edge of its blade in engagement with a rotating surface, pistons carried by said frame members and fitting within said trunnion housings, and valve means located in one housing and operated by relative movement between said housing and piston for controlling the admission of a fluid operating medium to the trunnion housings, to impart a back and forth movement to said blade carrier with respect to said pistons and frame members, in a direction parallel to the axis of said rotating surface.
